UNITED STATES PATENT OFFICE.

MAURICE METZGER, OF MONTREAL, QUEBEC, CANADA.

PHOTOGRAPHIC-PRINTING MACHINE.

Application filed July 11, 1925. Serial No. 42,912.

This invention relates to new and useful improvements in photographic printing machines and the object of the invention is to provide a simple device of the class stated which will expose a print a plurality of times to enhance the appearance of the print by providing same with a border, title, reference or any other such useful or decorative addition when said print is developed.

Another object is to provide a machine of the class stated which will automatically accomplish the above objects in one cycle of operations.

A further object is to provide a machine which will automatically control the time that the print will be exposed to light.

A still further object is to provide a simple means for gripping the print when it is inserted in the machine and also to provide a simple means which will release the print after all the exposures have been accomplished.

A still further object is to provide a machine of the class stated which will be very easily controlled and manipulated by unskilled labor once the machine is set for proper exposures.

The device consists briefly of a base having a plurality of sets of gripping fingers secured to a rotatably mounted turret and adapted to engage with the upper edge of a ring to regulate their rise and fall during the operation of the machine. Each set of fingers is adapted to grip a piece of printing paper and place same over electrically lit chambers covered with glass or such like transparent material. The glass covers are provided with masks which allow certain features of negatives placed thereon to be transferred to the printing paper by light in the well known manner. The turret moves in a rotary direction carrying the fingers with it, said fingers being mounted on the ring so that the paper is placed over the chambers and so that each paper will be subjected to two or more exposures which will enhance the print once same has been developed. Means are provided for positioning the print in the fingers and also for releasing same after they have been exposed.

In the drawings:-

Figure 1 is a perspective view of the bed plate of the machine showing the mechanism mounted thereon.

Figure 2 is a plan view of the machine

with minor parts of the machine removed to clarify the construction of same.

Figure 3 is a side sectional elevation of the machine taken on the line 3—3 Figure 2.

Figure 4 is a side sectional elevation of the machine taken on the line 4—4 Figure 2.

Figure 5 is a plan view of the turret with the printing paper gripping fingers attached thereto.

Figure 6 is a perspective view of the stop mechanism for use with the presser arms said view being taken from the back of the machine.

Figure 7 is a view of one of the light controlling switches and its operating mechanism.

Figure 8 is a perspective view of a relay switch controlling the light which controls the bordering of the print.

Figure 9 is a perspective view of one set of the gripping fingers for the printing paper.

Figure 10 is an elevation showing the pawl for holding the fingers in their print receiving position.

Figure 11 is a perspective view of the turret stop and releasing mechanism.

Figure 12 is a perspective view of the paper positioning means and the negative holder.

Figure 13 is a plan view of the turret revolving cam connection to the plunger operating same.

Figure 14 is a side elevation of the device in Figure 13.

Referring more particularly to the drawings, 21 designates the bed plate of the machine which in the machine shown is a table top supported on legs 22. Apertures 23 and 24 are cut in the top in close proximity to the sides 25 and 26 respectively and at the same radius from the centre of the table. Mounted in the apertures which are rectangular in shape are the sheets 27 and 28 of glass or other transparent material through which the light from the lamps 29 and 29^a are reflected through the medium of the chambers 30 and 31 the inner surfaces 32 of which are covered with light reflecting material. The light from the chamber 30 may be used for printing the main or centre portion of a photographic negative or film laid on the glass 27 but not shown in the drawing.

A photographic mask not shown but of any of the well known types may be placed over 110

the glass 27 so that only part of the negative laid thereon may be transferred to the printing paper in the manner hereinafter described. The light from the chamber 31 may be used for exposing the remaining part of the paper so that a border may be formed thereon when the paper is developed. The machine shown is only designed for two operations but it will be readily understood that the number of light reflecting chambers may be increased so that additional marks, ornamental or otherwise or even names may be printed on the printing paper. Mounted on suitable bearings 33 in the centre of the table is a turret designated as a whole by the numeral 34. The turret has an upwardly projecting portion 35 into which a stud bolt 36 or such like centering means may be placed to hold the turret in position. The bolt 36 is placed through a lug 37 forming part of a bracket 38 hereinafter described. The lower portion 39 of the turret in the machine shown, is of rectangular formation, the outer edges 40 of which are formed to receive a hinge pin 41^a upon which are mounted the printing paper gripping fingers a detail of which is clearly shown in Figures 5, 9 and 10. Attached to the portion 39 of the turret by means of the hinges 40 are the fingers 41 and 42, which extend outwardly from said hinges and are so positioned that they will hold a piece of printing paper over the apertures in the top with its edges parallel to the inner edges 43 and 44 of said apertures. The lower fingers 41 may be made of heavier material than the upper fingers 42 which are made of spring ribbon steel, so that bars 45 placed between them may raise the free ends of the upper fingers clear of the lower fingers when said bars are pivoted about their edges 46. The bars are held in place between the fingers and midway between their fixed ends 47 and their free ends 48 by means of the pins 49 passing through the lower fingers 42. Extending from the bars towards the centre of the machine are the finger opening levers 50 adapted to engage with pawls 51 pivotally secured to brackets 52 secured in any suitable manner to the inner portion or ends 47 of the fingers as shown or to the hinges. The pawls are rotatably mounted on the pawl pins 53 and spiral torsion springs 54 may be mounted on the pins and engage with the pawls in such a manner that the notches 55 formed in the pawls tend to engage with the ends 55^a of the bars. The brackets 52 may be joined together by any suitable means such as the ribs 56. The lower ends 57 of the pawls extend below the level of the fingers so that they will engage with finger closing mechanism hereinafter described. The fingers rest upon a jng 58 secured to the centre of the table by a suitable means. The uppermost edge 59 of the ring is of irregular shape so that the fingers will ride clear of the table when the turret is revolving and rest upon the glass over the aperture at two positions when the turret is at rest. A notch 60 is formed in the ring to allow the free end of the fingers to dip towards the surface of the table at one part of the machine so that printing papers may be easily inserted between the fingers. At this point the fingers are brought together to hold the paper firmly during the operation of printing. The edge of the ring then gradually slopes towards the border printing apertures 24 which is positioned at right angles to the aperture 23 and to the notch 60. This slope is gradual so that the motion towards the aperture 25 will be smooth and not tend to shake the paper from the grip. The remaining portion of the edge of the ring is adapted to raise the papers clear of the table until they are released.

Extending from side to side of the machine and mounted on brackets 61 is the presser arm supporting shaft 62 which also assists in supporting the cantilevered end 63 of the bracket 38 which extends over the turret mechanism and carries the lug 37. The end 64 of the bracket 38 is secured to the bed plate by means of the screws 65. Mounted or made integral with the lower portion of the turret is the upper portion 66 having upwardly projecting pins 67 which form part of the turret moving mechanism. These pins are spaced equidistant from one another and at a fixed radius from the centre of the turret. A plunger 68 is slidably mounted in bearings 69 formed integral with the bracket 38 and is connected at one end 70 to a turret pin engaging cam 71. The end 70 is slotted (see Figures 13 and 14) to receive said cam which is pivotally mounted on a pin 72 passing through the end 70. The cam is provided with a groove 73 which engages with the pins 67 and is so formed that it will clear the adjacent pin during the rotation of the turret. To hold the cam in engagement with the pin 67 a compression spring 72^a is mounted between the bottom of the slot and the end 74 of the cam in such a manner that there is always a tendency for the cam to rotate towards the centre of the machine. The end 75 of the plunger is pivotally connected to one end 76 of a bell crank lever 77 by means of a link 78. The bell crank lever is rotatably mounted on a pin 79 passing through an upwardly extending bracket 80 formed integral with the bracket 38. The other end 81 of said bell crank lever has a counterbalance weight 82 depending therefrom and supported by a wire 83 passing over a slot 84, so that the weight may be very easily dismantled. Also depending from the lever end 81 is a piston 85 which slides in a cylinder 85^a secured in any suit-

able manner to the bed plate. The cylinder is filled with a fluid which checks or retards the rapid movement of the mechanism during the rotation of the turret by forming a cushion or dashpot. Depending also from the free end 81 of the lever is the plunger operating link 86 which is pivotally attached to the lever by means of the pin 87. The free end of the link is provided with an open ended slot the sides of which embrace a pin 89 passing through the presser arms 110^a. Pivotally attached to the pin 89 is the connecting rod 90 which is pivotally secured to one end 94 of a double ended lever 91 pivotally mounted on a pin 92 passing through a bracket 93 secured to the underside of the bed plate. The other end 95 of the lever 91 is attached to a link 96 which is connected to a foot lever 97, suspended from the underside of the bed plate. The foot lever shown is of U formation and extends across the machine. On one of the upwardly extending arms 98 of the foot lever, a pawl 99 is mounted and adapted to engage with a toothed rack 100 secured to any fixed part of the machine. The pawl is freely mounted on the arm on a pin 101 and prevents backward movement of the foot lever before its full stroke is completed by engaging with the teeth in the rack. The upper portion 66 of the turret is provided with outwardly extending arms 102 through which screws 103 may be placed to form stops for limiting the movement of the turret during each stroke of the foot lever. The screws may be adjusted to suit the position of the stop mechanism which comprises a gravity operated pawl 104 pivotally mounted on a bracket 105 extending outwardly from and at right angles to the cantilevered end 63 of the bracket 38. The pin 106 supporting the pawl 104 passes through the bracket 105 and has a releasing lever 106^a secured thereto and adapted to engage with the fingers when they are raised during the operation of the machine. A stop pin 107 projecting outwardly from the pawl engages with a lug 108 formed in the bracket 105 to limit the downward movement of the pawl. Pivotally attached to a shaft 109 passing through the end 110 of the presser arms 110^a is the presser plate 111 which is made in two parts 112 and 113. The part 113 is provided with upwardly projecting pins 114 which pass through apertures 115 formed in the part 112 and compression springs 116^a surrounding said pins and positioned between the parts form a cushion for the part 113 and allow it to adjust itself to the table level. The pins 114 are provided with means to lock the parts 112 and 113 together. Projecting upwardly and rearwardly from the part 112 is the guide arm 116 which engages with a pin 117 secured to the bracket 108 project-

ing outwardly from the cantilevered end 63 of the bracket 38. A tension spring 120^a may be connected between the arm 116 and the presser arm to hold the end 119 of the arm 116 in contact with the pin 117. The border printing presser arm 120 is pivotally attached to a bracket 121 secured to the table and is operated by the movement of the photograph presser arm 110^a by engaging with the shaft 109 which passes through a slot 122 formed in the free end 123 of the arm 120. The border presser arm is also provided with a presser plate 124 made in two parts 125 and 126 similarly connected as the parts 112 and 113, so that said presser plate 124 will adjust itself to the level of the table. The parts 113 and 126 are approximately the same size as the apertures 23 and 24 and are adapted to cover same when the machine is in operation. Felt pads 127^a may be provided as a cushion for said plates. The fingers are raised at one point in the operation of the machine by means of the rod 127 slidably mounted in a slot 128 cut in the bed plate and connected at its lower end to one end of the finger raising bell crank lever 129 pivotally attached to a bracket 130 secured to the underside of the bed plate. The other end 131 of the bell crank lever 129 is connected to a pin 142 passing through the arm 95 of the double ended lever 91 by means of a link 132 which is provided with a slot 134 at one end to allow the lever 91 to move a certain amount without moving the link 132. A tension spring 135 may be attached to the rod 127 to hold it in the vertical direction. The end 136 of the rod engages with screws 137 passing through the hinge of the fingers. These screws may be easily adjusted to give the proper lift to the fingers. The pawls which hold the fingers in their open position are released by the radial movement of the rod 138, which is pivotally attached to the bracket 130 and operated by the movement of the bell crank lever 91, through the medium of the link 139, one end of which is pivotally attached to the rod by means of the pin 140 while the other end of said link is provided with an open ended slot 141 in which the pin 142 is slidably mounted. A tension spring 143 may be provided to hold the rod 138 against the end 144 of the slot 145 formed in the bed plate. This rod also transmits horizontal movement to a plate 146, the edge 147 of which is positioned to form a guide for the edge of the printing paper to raise same so that it will pass between the fingers when they are in the open position. A negative holding device 125 is mounted on the frame in close proximity to the edge 148 of aperture 23 and comprises three blocks 149 mounted on a pin 150 secured to the brackets 151 attached to the bed plate. The blocks are held against the 130

bed plate by means of the tension springs 152 attached to a fixed pin 153 mounted in brackets below the bed plate. To raise said blocks vertical moving pins 153^a are provided, each pin projecting upwardly through the bed plate and engaging with one of the blocks. The pins are secured at one end to a U-shaped bar or lever, the arms 154 of which are pivotally mounted on pins 154^a passing through said arms midway between their ends. A U-shaped operating lever 155 is attached to the end of said arms and extends above the top of the table so that the palm of the hands of the operator 15 may be used to operate the blocks when placing the negative in position. Depending from the arms 110^a is the finger opening link 156 which engages with the finger operating levers or bars and depresses same until 20 the notch in the pawl engages with the end of said bar as aforementioned. A gravity operated stop bar 157 is pivotally mounted on the bracket 80 and is adapted to engage with the pin 89 during the operation of the 25 machine. The upper end 158 of the bar 157 is rectangular as shown in Figure 6, so that a pin 159 secured to the bell crank lever will engage with the corner 160 of said end to swing the stop bar clear of the pin 89 30 during the operation of the machine. Springs 161 are placed between the fingers to hold them from side movement on their hinges. The lights may be automatically controlled by the motion of the foot lever. 35 The lighting switch for the photographic printing chamber is shown in Figure 7, and the border printing lighting switch is shown in Figure 8.

Referring to Figure 7, the switch is indicated by the numeral 162 and is provided with a tension spring 163 attached to the controlling handle 164 to hold the switch in its off position. Secured to one of the arms of the foot lever is the bracket 165 having a screw 166 projecting therefrom and adapted to provide an adjusting means to regulate the stroke of the switch. The screw contacts with the side 167 of the lever 168 projecting out from one side of the 50 downwardly projecting ledge 169 of the table or bed plate. The upper end 168^a of the lever 168 is attached to the switch controlling handle by means of the rod 170. Now referring to Figure 8 which shows a 55 relay switch, the contacts are designated 171 and 172. Contact 172 is fixed to a pivotally mounted lever 173 and contact 171 is pivotally mounted on a pin 171^a. The end 174 of the lever 173 to which the contact 60 is fixed is bevelled and the projecting end 176 of the contact 171 is also bevelled so that a pin 177 controlled by the movement of the connecting rod 90 will reset the switch. The coil 179 while current is passing 65 through it is energized and pulls a spring

catch 180 out of a notch 181 formed in the piston 182, working in a cylinder 183 filled with a fluid. The resistance of the fluid to the movement of the piston regulates the time the lever 173 will take to bring the contacts controlling the light to their "off" position as the piston is connected by means of a link 184 to the end 185 of the lever 173, said end 185 being positioned on the opposite side of the pivot pin 186 supporting 70 said lever 173. Suitable covers 187 may be provided for the relay switch. The device may be subjected to various modifications without departing from the spirit of the invention. 75

An aperture 189 may be formed in the photographic printing arm presser plate to allow a numbering device 190 to pass therethrough to mark the back of the prints. The numbering device may be operated by a cam 191 attached to it, and contacting with a pin 192 secured to the presser arm. When the presser plate falls the cam allows the numbering device to contact with an inking roller 193 and to pass same until it has assumed a vertical position so that a number may be printed on the back of the print. Many such devices may be used and the device shown is only diagrammatically shown to 85 illustrate one feature of the machine. The machine shown is manually operated, but it will be readily understood that the device may be electrically operated without departing from the spirit of the invention. 90

In operation the turret rotates through an angle of 90° or one quarter of a revolution for each double stroke of the foot lever. There are four sets of fingers on the turret and from the time the printing paper is placed between the fingers until it is discharged therefrom, it passes through an arc of 270° or three quarters of a circle. While the machine is in operation photographic printing papers are held in at least three sets of the gripping fingers. The photographic negative is placed over the aperture 23 and a suitable mask is placed over or under said negative so that only the center portion of the negative will be printed. The negative and mask are held in place by means of the blocks 149 which are raised by pressing the lever 155 downwardly, the tension springs pull the blocks towards the bed plate as soon as lever 155 is released thereby locking the negative in position. The set fingers opposite the aperture 23 are in the open position ready to receive a sheet of photographic printing paper. The foot lever is pulled towards the operator. The pin 142 pushes the rod 138 towards the aperture 23 carrying the plate 146 forward. This plate or guide 146 is approximately equal in thickness to the lower fingers 42 and papers placed on said plate are guided between the fingers and are positioned by 100

means of the blocks. The movement of the rod also releases the pawl holding the fingers and the spring fingers grip the paper. The foot lever is then pushed away from the 5 operator to bring the presser plate in contact with the paper lying above the negative in the aperture 23. This is accomplished through the medium of the connecting rod 90 and lever 91. The projecting arm 10 on the presser plate contacts with a cam or pin on the presser arms to gradually bring it into the horizontal position when it reaches its lowermost point. Then pin 89 contacts with the slotted bar 86 which pulls 15 the turret turning cam, so that it will engage with one of the pins projecting upwardly from the turret. The light in the chamber 30 is also lighted through the pushing movement of the foot lever. The downward 20 movement of presser arm also carries the presser plate 124 over the aperture 24 upon which a mask designed to print a border on the printing paper held between the fingers opposite said aperture and which are holding 25 a partially finished print over the aperture 24, and chamber 31 the lights in which are controlled by a relay switch operated by the movement of the foot lever and controlled by the dashpot. The lights in chamber 30 are in parallel with the lights in chamber 30 and the current supply is controlled by the switch 162. The current passes through the contacts 171 and 172 and through the coil 179 which when energized 35 releases the spring catch 180 allowing piston 182 to drop. The resistance of the fluid in the cylinder regulates the time that contacts 171 and 172 remain in their "on" position. Pin 177 operated by the movement of the rod 40 90 resets the contacts and allows the spring catch to hold the piston until released by the action of the coil. Stop bar 157 is used as a safety device to prevent the foot treadle from being operated faster than the dashpot. 45 85^a will allow the turret to rotate and only comes in contact with the pin 89 in the event of the treadle or foot lever being pushed forward before the turret has come to rest. The turret is held against movement by the 50 stop pawl 104. On pulling the foot lever towards the operator, the presser arms are raised from contact with the glass and the switches controlling the lights in the chambers are allowed to return to their "off" 55 position. On its return movement, the pin 142 contacts with the end of slot 144 and pushes the rod 127 upwardly to raise the finger clear of the notch in the ring and also raises the paper clear of aperture 23. The 60 upward movement of the fingers releases the stop pawl 104 through contacting with the lever 106^a and allows the weight 82 to push the turret through an angle of 90° or until it contacts again with the stop pawl 104. 65 The weight pulls on the lever 77 which pushes the plunger and turret engaging cam, and the dashpot 85^a and piston 85 prevents a too rapid movement of the turning of turret. On downward movement of the arm 81, the pin 159 releases the safety pawl 157 70 which is designed to prevent the presser from being operated should the turret through some unforeseen circumstance refuse to operate. The turret has then moved through an angle of 90° and is again ready for 75 the insertion of an unexposed printing paper. The printing papers are released at the point X during the downward stroke of the presser arm 110^a which carries the releasing bar 156. The end of this bar contacts with the bar 50 pressing same downwardly and allowing the pawl 51 to engage with the end of the bar to hold the fingers in their open position. As will be seen from the foregoing all parts of the machine are controlled 80 by the movement of the foot lever, except the negative holding blocks which are easily operated by the palms of the hand of the person inserting the negatives. The machine positions the printing paper and subjects it to a plurality of exposures so that it will improve the appearance of the print when it is developed by providing same with a border, artistic or otherwise. The prints may also be numbered by means of the numbering 85 mechanism mounted on the presser plate. The device is very simple in operation and may be operated by an unskilled party. 90

Having thus described my invention, what I claim is:—

1. In a photographic printing machine, a plurality of photographic printing paper holding means, a plurality of printing frames equipped with complementary negatives, mechanical means for operating the paper holding means to pass the printing paper over each frame and means for automatically guiding each holding means so that the printing paper will be subject to successive exposures from said frames in 105 its passage through the machine.

2. In a photographic printing machine, a plurality of paper holding means adapted to rotate about a common centre, a plurality of photographic printing frames spaced 110 equidistant from one another and from said centre, said printing frames being equipped with complementary negatives for successively printing different portions of a composite picture on the printing paper when the latter is exposed thereto, means for guiding the papers held by the holding means over each of the printing frames in turn, means for simultaneously clamping the papers over each of the printing frames and means for controlling the light exposure in each frame and to rotate the paper holding means.

3. In a photographic printing machine, a plurality of paper holding fingers adapted 120

125

130

- to rotate about a common centre, a plurality of printing frames equipped with complementary negatives, means for bringing the printing papers over each frame as it passes through the machine, means for simultaneously clamping a piece of printing paper over each frame, means to hold the printing papers in position during exposure of same and means for controlling the rotative movement of the fingers.
4. In a photographic printing machine, a plurality of paper holding fingers, adapted to rotate about a common centre, a plurality of photographic printing frames having masks mounted thereon displaying different characteristics, means for guiding the printing papers so that they will each be subjected to an exposure from each frame, means for simultaneously clamping a paper over each frame, and means controlled by the clamping means to discharge one paper at a time from said fingers.
5. In a photographic printing machine; a plurality of hingedly mounted fingers adapted each to hold a printing paper, a plurality of printing frames equipped with complementary negatives, gravity operated means for rotating said fingers to simultaneously place the printing papers over each frame, mechanical means for raising the rotating means to operate independent of the mechanical raising means and means to absorb the shock caused in a gravity operated means.
6. In a photographic printing machine a plurality of photographic printing frames, equipped with complementary negatives, lights in said frames, a plurality of paper holding means rotatably mounted and adapted each to place a paper over each frame, means for simultaneously clamping a paper held in said fingers over each frame, means to guide the fingers so that each paper is subjected to one exposure from each frame, means for simultaneously controlling the lights in each frame to suit the exposure required, means operated by the clamping means to successively come in contact with each of the fingers to release the paper held therein, once it has been subjected to all the exposures required.
7. In a photographic printing machine, a plurality of printing frames equipped with complementary negatives, electrically lighted chambers under each frame, a revolving turret, a plurality of gripping devices extending from said turret and attached thereto, said gripping device being adapted to carry a plurality of papers, means to rotate said turret to bring each of said papers over each frame and means operated by the rotating means to control the lights.
8. In a photographic printing machine a plurality of printing frames equipped with complementary negatives, electrically lighted
- chambers under each frame, a revolving turret, a plurality of hinges secured to the turret, spring gripping fingers extending outwardly from said hinges, to carry a plurality of printing papers, means to revolve said turret, means to control the lights in the chambers, and means to restrict the movement of the turret so that each printing paper will be subjected successively to the lights in said chambers.
9. In a photographic printing machine, a bed plate, a plurality of printing frames in said bed plate, said printing frames being equipped with complementary negatives, a revolving turret mounted on said bed plate, a plurality of electrically lighted chambers under each frame, a plurality of spring gripping means hingedly secured to said turret, said gripping means extending outwardly from the turret and adapted to carry a plurality of papers, means to successively guide the papers held by said gripping means so that they will be submitted to an exposure from each of the printing frames, gravity operated means to rotate the turret, mechanically operated means for raising the rotating means and to control the lights in said chambers, means engaging with the turret and released by the movement of the fingers to align the printing papers over their respective frames, and means to retard the movement of the turret during its rotation.
10. A photographic printing machine, according to claim 9 having means actuated by the raising means to simultaneously clamp a printing paper over each frame and means operated by the clamping means to release the papers from the fingers once they have been exposed to all the lights in the chambers.
11. In a photographic printing machine, a bed plate, a plurality of electrically controlled exposure chambers formed in said plate, said chambers being equipped with complementary negatives, a turret rotatably mounted on said plates, a plurality of spring gripping fingers, hingedly attached to said turret, means mounted on the bed plates to successively guide the fingers towards each of said chambers during the rotation of the turret and to lift said finger clear of the bed plate between each of the chambers and means to automatically control the movement of said turret and the lights in said chambers
12. In a photographic printing machine, a bed plate, a plurality of chambers formed in said bed plate and equipped with complementary negatives, electric lights in each of said chambers, rotatively mounted means for holding a plurality of printing papers, means to guide each of said papers to lie successively over negatives placed over each of the chambers, means to control the movement of the holding means and the lights in

said chambers and means to automatically release the papers from said holding means once they have been submitted to an exposure from each of the chambers.

- 5 13. In a photographic printing machine, a plurality of photographic printing frames equipped with complementary negatives, a plurality of sets of photographic printing paper supporting fingers each adapted to 10 hold one sheet of paper, means to guide each set of fingers towards each frame, means to rotate the fingers, means to align and hold the fingers over each frame edge, means to

raise the fingers clear of the frame while passing between them, means to clamp each 15 print over each frame, means attached to the clamping means to release the print after it has passed through the machine, means to hold the fingers open to receive the print, 20 means to release the fingers to grip the paper, and means to align the print with the first frame and to guide the paper towards said fingers.

In witness whereof, I have hereunto set my hand.

MAURICE METZGER.
